US0D1087688S

(12) **United States Design Patent** (10) **Patent No.:** **US D1,087,688 S**
(45) **Date of Patent:** **** Aug. 12, 2025**

(54) **CONTAINER LID**

(71) Applicant: **Hydrojug, Inc.**, Ogden, UT (US)

(72) Inventors: **Hayden Wadsworth**, Ogden, UT (US);
Ethan Powell, Salt Lake City, UT (US);
Ryan Holmes, West Haven, UT (US)

(73) Assignee: **HYDROJUG, INC.**, Ogden, UT (US)

(**) Term: **15 Years**

(21) Appl. No.: **29/935,235**

(22) Filed: **Mar. 30, 2024**

(51) **LOC (15) Cl.** **07-02**

(52) **U.S. Cl.**

USPC **D7/392.1**; D7/392

(58) **Field of Classification Search**

USPC ..... D9/443, 449, 500, 516, 549; D7/300, D7/392, 392.1, 396.2, 509, 510, 511, 514, D7/533, 543, 600, 619.1, 900; D3/202 CPC A47G 19/2205; A47G 21/18; A47J 41/00; A47J 41/028; B65D 1/00

See application file for complete search history.
